SOCKET FOR ELECTRIC DISCHARGE LAMPS

George C. Salneu, Havertown, Pa.

Application January 28, 1947, Serial No. 724,764

4 Claims. (Cl. 173—328)

1

The invention relates to sockets for electric discharge lamp terminations, and, more particularly, to compression spring contacts for such sockets.

Heretofore, sockets for electric discharge lamp terminations have been provided with guarded contacts comprising compressible helical springs positioned in the sockets in spaced relation from the socket mouth. It is possible for such springs to become welded to the termination contacts of high-voltage lamps and on removal of the lamp to be elongated or pulled out into a position where they constitute an electric shock hazard to maintenance personnel. This condition might also occur with the spring contact of the luminaire socket described in my copending patent application, Serial No. 664,148, filed April 23, 1946, now United States Patent No. 2,486,497, issued November 1, 1949, for a termination for electric discharge lamps, in which the spring is engageable with a recessed contact in the lamp termination.

The primary object of my invention is to provide an electric discharge lamp socket in which this defect is overcome.

Another object of my invention is to provide an electric discharge lamp socket having a resiliently compressible contact member of restricted extensibility constituting a guarded contact having a fixed minimum depth from the mouth of the socket.

A further object of my invention is to produce an electric discharge lamp socket having a helical compression spring contact member provided with means incorporated in the contact member and co-operative with an element at its base for limiting its expansion.

Still another object of my invention is to provide an electric discharge lamp socket with a helical compression spring contact member having inexpensive, simple, durable and effective means for limiting expansion to a predetermined length while permitting a desired degree of collapse.

With these and other objects in view which will appear from the ensuing description and claims, the following sets forth specific embodiments of my invention which are described as examples and illustrated in the accompanying drawing, in which—

Fig. 1 is a fragmentary view, partly in section, of the electric discharge lamp luminaire socket of my invention and the associated lamp termination.

Fig. 2 is an enlarged view of the helical spring of the socket of Fig. 1.

2

Fig. 3 is a fragmentary perspective view of the spring of Fig. 2 showing details of the construction of the top part.

Fig. 4 is a fragmentary perspective view of the spring of Fig. 2 showing details of the construction at the bottom.

Fig. 5 is a side elevation of the upright hook member of the socket of Fig. 1.

Fig. 6 is a fragmentary side elevational view of parts of the socket of Fig. 1, showing details of assembly.

Fig. 7 is a side elevational view of a modification shown in extended position, of the spring and elongation restricting means.

Fig. 8 is a side elevational view of the device of Fig. 7, with the spring in partially collapsed position, showing details of construction.

Fig. 9 is a side elevational view of a further modification of the spring and restraining means, with the spring shown in extended position.

Fig. 10 is a side elevational view of another modification of the spring, shown in fully extended position.

Fig. 11 is a side elevational view of the spring of Fig. 10, shown assembled to the mounting screw and compressed toward it.

Fig. 12 is a fragmentary side elevational view, partly in section, showing the device of Fig. 11, as it would appear after relieving the compression.

Fig. 13 is a fragmentary perspective view of the body of the socket of Fig. 1, showing the spring mounting plate in assembled position relative to the body.

Figs. 14 and 15 are fragmentary sectional elevations of another modification of my electric luminaire socket showing a lamp termination respectively just making contact with and fully depressed within the socket.

Fig. 16 is a developed plan view of the spring of Figs. 14 and 15.

Referring to the drawing, I have shown in Fig. 1, one end of a high-voltage cold-cathode type lamp having a termination 15, comprising a tubular glass shell 16, enclosing a metallic disk contact button 17, wires 18 welded to an electrode 19 and the contact 17, and a glass sealing bell 20. The bell 20 has a cupped recess 21 and is ring-sealed to the outer end 22 of the glass shell 16. The termination 15 is engageable with a female body or socket 25 which is of generally conventional type having a substantially cylindrical hollow body 26 of glass or other electric insulating material provided with screw threads 27 to engage a threaded metal collar 28 for

55

mounting in a luminaire (not illustrated). However, I have replaced the large-diameter helical contact spring of the receptacles presently available with a helical contact spring 30 of diameter small enough to enter freely the recess 21 of the bell 20 and engage the contact 17.

The spring 30 projects freely from the base of the body 26, without external obstruction, and is mounted coaxially therein by means of a screw 31, spring mounting plate 32, retaining plate 33 and nut 34. A lead 35 to an electric circuit, not illustrated, is attached externally of the body 26 to the screw 31 by the usual nut and washer means. The screw 31 is of the carriage-bolt type non-rotatably attached to the body 26 by having its tapered square neck 36 engageable in a square hole 37 in the mounting plate 32 which is provided with depending flanges 38 adapted to engage the slotted bottom opening 39 of the body 26. The lower part of the screw 31 passes through a drilled opening in the retaining plate 33 which is of elongated shape adapted to pass through the opening 38 when its longer axis is aligned therewith and to obstruct such passage when positioned at right angles thereto. The assembly of screw 31, mounting plate 32, body 26 and plate 33 is held firmly together by tightening the nut 34 which engages the screw 31 below the plate 33. Projections 40 on the upward side of the plate 33 prevent rotation thereof by engaging the outer side rim of the slotted opening 39.

The spring 30 is formed of resilient wire of requisite stiffness to maintain its central position and engagement with the contact 17, and is of generally helical shape tapering slightly toward the top. At the top 45 the wire is formed into a transverse-plane inward spiral for approximately a complete turn, then extends straight downwardly for approximately half the desired extended length of the spring, then describes a U-turn, and finally extends straight upwardly to terminate just short of the top 45, thereby forming a downward hook member 46. At the bottom 47 of the spring 30 the wire is spiralled inwardly to a circular arc of somewhat less than a complete turn, concentric with and perpendicular to the axis of the spring, and engageable with the neck 36 of the screw 31.

An upright hook member 48 comprises a wire similar to that of the spring 30 formed into an open ring 49, which may or may not be flattened as illustrated and is engageable with the neck 36 of the screw 31, then bent sharply upward at the point 50, and finally bent into an inverted U-shape with a sharp curve 52 at the top and terminating with its end 53 a short distance above the ring 49. Between the bend 50 and the top 52, the wire is provided with an inflected curvature 51 so that it may pass between the two bottom end turns of the spring 30 as will be presently described.

The spring 30 and hook member 48 are assembled to the screw 31 in the manner illustrated in Figs. 2 and 6. The hook member 48 is first assembled to the spring 30 with its loop 52 engaged by the downward hook 46, which is readily accomplished by fully compressing the spring 30, and with its ring 49 disposed beneath the end turn 47. In this condition the relation of the parts is such that the spring 30 is under slight compression. The spring 30 and the hook members are so arranged that when the lateral openings in the ring 49 and end turn 47 are aligned to receive the neck 36 of the screw 31, the cooperating hooks 46 and 48 will lie in mutually per-

pendicular vertical planes and the curvature 51 will clear the inside of the widest part 54 of the second turn from the bottom of the spring 30. The ring 49 of the hook member 48 is adapted to receive the neck 36 of screw 31 with a snug fit and permit clearance of the head 55 inside the upward bend 50.

The assembly of spring 30, hook member 48, mounting plate 32, retaining plate 33 and nut 34 loosely attached to screw 31, is dropped screw foremost into the socket 25. The bottom of the body 26 is smoothly curved toward the slot 39 so that the nut 34 and retaining plate 33 drop through the slot 39, and the mounting plate 32 guided by the flanges 38, comes to rest in transverse locking position as illustrated in Fig. 13. It is then a simple matter to turn the plate 33 to transverse locking position, center the assembly in the slot 39, and tighten the nut 34 to obtain the desired rigidity. Because the end 53 of the upright hook member 48 is in close proximity to the head 55 of the screw 31, and the free end of the downward hook member 46 terminates just short of the top of the spring, it is practically impossible to completely separate the hook members even when the spring is deliberately compressed to the limit.

It will be noted that the electric contact button 17 is longitudinally recessed in the mouth of the lamp termination to a depth greater than the diameter of said mouth, and similarly the outer end 45 of spring 30 is at all times maintained at a depth from the open end of the body 26 greater than the diameter thereof.

The operation of the device is as follows. With the parts disposed as illustrated in Fig. 1 with the spring 30 under slight compression, the termination 15 is inserted into the socket 25 until the end 22 touches bottom in which position it is arranged to be held by the usual external clamps or ties (not illustrated). As the termination is moved into the socket, the bell 20 engages and moves down over the spring 30. Well before the end 22 reaches the bottom of the socket, the contact button 17 meets the top turn 45 of the spring, after which further movement merely compresses the spring causing the hook members 46 and 48 to slide along each other. The spring and termination are so proportioned that the spring is not compressed to its limit when the end 22 of the termination comes to rest in the bottom of the socket. On removing the termination 15 from the socket 25, the spring 30 expands until the hook members 46 and 48 re-engage at the predetermined desired spring length.

Figs. 7 and 8 show a modification of my invention in which a spring 60 is restrained by a flexible pigtail 61. The spring 60 is similar to the spring 30 except that it is brought to a plane turn at the top as a seat for a metal button 62 having an apertured shank 63 and a flat top comprising the electric contact. The pigtail 61 is looped through the aperture or eye of the shank 63 and both ends passed down inside the spring 60 and brought out between its last two turns at the bottom. The ends of the pigtail are then inserted into the hollow end 64 of a compression-connector type lug 65 and suitable compression is applied to make a permanently tight connection. The lug 65 has a ring 66 adapted to fit the neck 36 of the screw 31, and a relatively long shank 67 which is bent up and inwardly to clear the head 55 of the screw 31. In assembling this device, the spring 60 is compressed as shown in Fig. 8 while the lug 65 is being attached to the ends of

the pigtails 61 after which the spring 60 is released. The assembly then appears as illustrated in Fig. 7 with the spring 60 under slight compression. To attach to the screw 31, the spring is compressed as in Fig. 8, the screw inserted in the ring 66, then slipped sidewise into the bottom end turn 67 of the spring 60. The assembly is then attached to the socket 25 as previously outlined for the modification of Figs. 1 to 6.

The modification illustrated in Fig. 9 is similar to that of Figs. 7 and 8 in having the lug 65 compression-connected to a flexible pigtail 72. However, in this case the spring 70 differs from the spring 60 in having the top end spiralled inwardly and then turned downwardly as in spring 30 but terminating at the lower end in an eye 71. The pigtails 72 is looped through the eye 71 and then connected to the lug 65 as in the modification of Figs. 7 and 8.

Figs. 10 to 12, inclusive, illustrate a further modification which has a spring 80, similar to the spring 70, but in which the wire 81 descending from the top is axially disposed and, with the spring in unstressed condition, extends through and past the bottom end 82 thereof. The screw 83 of this device is similar to the screw 31 except that it has an axial hole therethrough. For a short distance downwardly from the top or head end of the screw 83, this hole comprises a bore 84 slightly greater in diameter than the wire 81 then continues through the screw with a bore 85 of considerably enlarged diameter. The wire 81 is inserted into the bore 84 of the screw 83 which is then slipped sidewise into the bottom end turn 82 of the spring 80. The spring 80 is then fully compressed so that the wire 81 protrudes below the screw 83 and a bead or enlargement 86 is formed at the end of the wire 81 by swaging, melting, bending over, flattening or the like. The bead 86 is freely movable in the bore 85, but is too large to enter the bore 84 and has its top edges rounded to prevent binding at the juncture of the bore 85 with the bore 84. When the spring is released from the compressed position shown in Fig. 11, it expands and draws the bead 86 up through the bore 85 until the bead is stopped by the constriction at the juncture with the bore 84 as illustrated in Fig. 12. The bead 86 is formed at such relation to the length of the wire 81 to give the desired length and slight compression of the spring 80 when in the released position. The device of Fig. 12 is assembled to the socket 25 in the manner previously described for the modification shown in Fig. 1.

Figs. 14 to 16, inclusive, illustrate another modification of my invention in which the helical spring is replaced by a bayonet contact member 90. The bayonet 90 is brazed, riveted or otherwise securely attached, both electrically and mechanically, to the midpoint of and perpendicular to a flat spring 91. The spring 91 has widened ends 92 and 93 transversely slotted in opposite directions to receive the neck 36 of the screw 31. The spring 91 is bent into oval shape with the slots in the ends 92 and 93 in register, and the ends 92 and 93 are sprung sidewise to admit the neck 36. On releasing the ends 92 and 93 they spring back to enclose the neck 36. The spring 91 is then assembled on the screw 31 to the body 26 with the mounting plate 32 and retaining plate 33, as illustrated in Fig. 14, with the bayonet 90 firmly disposed in upright central position within the body 26.

As the termination 15 is depressed within the socket 25, the bayonet 90 is first engaged by the

contact 17 as illustrated in Fig. 14, and depressed thereby to the limiting position shown in Fig. 15, compressing the spring 91 until its midpoint engages the head of the screw 31. The balanced construction of the spring 91 insures the bayonet 90 being centralized over the entire range of movement. The length of the bayonet 90 is related to the depth of the contact 17 within the recess 21 so that the end 22 of the glass shell 16 at no time contacts the spring 91. On withdrawal of the termination 15 from the socket 25, the spring 91 will resist with increasing force outward movement of the bayonet 90 beyond the position shown in Fig. 14, and will disengage the bayonet from the contact 17 despite any tendency for these parts to become welded together.

It will be observed that in all examples of the invention illustrated and described herein the safety means for limiting the extensibility of the resilient contact member are incorporated in said member and include one or more elements which are co-operative with an element at the base of the socket. Thus the resilient contact member projects freely, without external obstruction, permitting guarded telescopic engagement between the lamp termination and the socket, and insuring that such contact will be maintained at a predetermined minimum spacing from the mouth of the body within which it is housed.

It will be also observed that in all of the examples of the invention illustrated and described herein a component of the resilient contact of the socket, either the spring itself or a stop element associated with it, serves to limit its extensibility and maintain the free end of the resilient contact at a depth from the open end of the socket not less than the diameter thereof. In all of the illustrated examples with the exception of the form of the invention shown in Figs. 14, 15, and 16 the spring is of a helical type and has incorporated within its convolutions a stop element for thus limiting its extensibility.

In the annexed drawings I have disclosed several species of the invention wherein the elongated stop piece for limiting the longitudinal movement of the contact element is itself generally longitudinally movable within the female body, such stop piece being illustrated in the form of the hook 46 of Fig. 2, the pigtails 61 of Fig. 7, the hook 71 and pigtails 72 of Fig. 9, the wire 81 of Fig. 10, or the resilient arms of flat spring 91 of Fig. 14. However it will be appreciated that the invention comprehends the substitution of equivalent stop elements serving to limit the extent of longitudinal movement of the contact element within the female body, and the connection of such stop means to the contact element and a fixed base in equivalent ways, all within the spirit of the invention as defined in the appended claims.

Although the invention has been described in considerable detail, such description is intended as illustrative rather than limiting, as there will be evident to those skilled in the art other embodiments and obvious modifications in construction and arrangement of parts, without departing from the spirit of the invention.

I claim:

1. In a socket for an electric discharge lamp termination having an electric contact, a female body of insulating material for receiving the termination, a guarded electric contact within said body including a helical compression spring with its base fixed to the bottom of said body, said

spring being engaged and compressed by said first mentioned contact when said termination is pressed into said body, and said spring being provided with an axially disposed hook member directed inwardly from its free end, and an upright hook member axially disposed within and fixed to the base of said spring, said hook members being maintained in interlocking relation with each other and being mutually engageable and of a length to limit the expansion of the spring to a length less than the internal depth of said body and to maintain it in recessed position within said body when said termination is removed from said body.

2. In a socket for an electric discharge lamp having an electric contact, a female body of insulating material for receiving the termination, a guarded contact within said body including a helical compression spring longitudinally disposed within and fixed to the bottom of said body in spaced relation to the sides thereof, said spring being engaged and compressed by said first mentioned contact when said termination is pressed into said body, and said spring being provided at its free end with a generally axial hook disposed within said spring and directed toward the fixed end, and a hook member fixed to the bottom of said body and disposed generally axially within said spring and slidably engaged with said hook, said hook and said hook member being maintained in interlocking relation with each other and being mutually engageable and of a combined length less than the internal depth of said female body to limit the expansion of the spring to a length less than the internal depth of said body when said termination is removed from said body, and to maintain the free end of the spring at a fixed minimum depth from the mouth of said body.

3. In combination, an electric discharge lamp termination having an open mouth at the end thereof and a guarded electric contact member longitudinally recessed in the mouth of said termination and fixed at a depth therein not less than the diameter of said mouth, and a socket comprising a female body of insulating material, within which said termination fits, a guarded resilient contact including a spring fixed to the

base of said body and projecting freely from the base of the socket towards the mouth thereof and yieldably movable longitudinally within said socket, the resilient contact extending into the recess of said termination to engage said contact member, elongated stop means connected to said resilient contact and engageable upon the base of said body to limit the extent of said longitudinal movement of the resilient contact, said elongated stop means being of such length as to maintain said contact at all times at a depth from the open end of said body not less than the diameter thereof.

4. In combination, an electric discharge lamp termination having an open mouth at the end thereof and a guarded electric contact member longitudinally recessed in the mouth of said termination and fixed at a depth therein not less than the diameter of said mouth, and a socket comprising a female body of insulating material within which said termination fits, a guarded electric contact within said body including a helical compression spring fixed to the base of said body and projecting freely from the base towards the open end thereof, the spring extending into the recess of said termination to engage said first mentioned contact member, a longitudinally extensible elongated stop element extending from the free end of said spring, axially disposed therein and fixed to the base of said body, to maintain the free end of said spring at all times at a depth from the open end of said body not less than the diameter thereof.

GEORGE C. SALNEU.
